CLAIM

The ornamental design for a body sculpting garment as shown and described.

DESCRIPTION

FIG. 1 is a front view of a first embodiment of a body sculpting garment showing my new design;

FIG. 2 is a rear view thereof;

FIG. 3 is a right side view thereof;

FIG. 4 is a left side view thereof;

FIG. 5 is a front view of a second embodiment of a body sculpting garment showing my new design;

FIG. 6 is a rear view thereof;

FIG. 7 is a right side view thereof; and,

FIG. 8 is a left side view thereof.

The broken lines shown in the drawings depict portions of the body sculpting garment that form no part of the claimed invention. The stippling in the drawings show shading that defines the contours of the design and does not reflect a particular surface ornamentation or material. The dotted lines in the drawings of the humanoid figure depicts environment and form no part of the claimed design.
